[57] CLAIM

The ornamental design for a fishing reel as shown and described.

DESCRIPTION

FIG. 1 is a front, top and right side of the perspective view of a fishing reel showing our new design;
FIG. 2 is a rear, top and left side of the perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom view thereof;

FIG. 9 is a front, top and right side of the perspective view of the other embodiment of showing our new design;

FIG. 10 is a rear, bottom and left side of the perspective view thereof;

FIG. 11 is a right side elevational view thereof;

FIG. 12 is a left side elevational view thereof;

FIG. 13 is a front elevational view thereof;

FIG. 14 is a rear elevational view thereof;

FIG. 15 is a top plan view thereof; and,

FIG. 16 is a bottom view thereof.
